United States Patent Office

Des. 222,748
Patented Dec. 21, 1971

222,748

COMBINED MINIATURE LAMP AND HOLDER THEREFOR

Bernard V. Strianese, Manhasset, N.Y., assignor to
Ackerman Engravers, Inc., Long Island City, N.Y.

Filed Feb. 24, 1970, Ser. No. 21,598

Term of patent 14 years

Int. Cl. D26—04

U.S. Cl. D26—8

Fig. 1

Fig. 2

Fig. 3

Fig. 4

Fig. 5

FIG. 1 is a perspective view of a combined miniature lamp and holder therefor embodying my design;

FIG. 2 is a bottom plan view thereof;

FIG. 3 is a top plan view thereof;

FIG. 4 is a side elevational view thereof;

FIG. 5 is a side elevational view thereof turned 90° from FIG. 4.

I claim:

The ornamental design for a combined miniature lamp and holder therefor, as shown.
